UNITED STATES PATENT OFFICE.

JAMES V. MOHLER, OF OELWEIN, IOWA, ASSIGNOR OF ONE-HALF TO CHARLES P. SMITH, OF OELWEIN, IOWA.

OIL-FEEDING DEVICE.

1,188,090.

Specification of Letters Patent. Patented June 20, 1916.

Application filed October 19, 1915. Serial No. 56,730.

To all whom it may concern:

Be it known that I, JAMES V. MOHLER, a citizen of the United States, and a resident of Oelwein, county of Fayette, and State of Iowa, have invented certain new and useful Improvements in Oil-Feeding Devices, of which the following is a specification.

My invention relates to improvements in oil feeding devices especially designed for use in connection with steam engines, and has for its object the production of a device of this character which will be of durable and economical construction, and one which will be highly efficient in use.

15 Other objects will appear hereinafter.

The invention consists in the combinations and arrangements of parts hereinafter described and claimed.

The invention will be best understood by reference to the accompanying drawings forming a part of this specification, and in which,

Figure 1 is a top plan view of a device embodying the invention, the top plate of the housing or body thereof being removed to expose underlying parts, Fig. 2 is a central vertical longitudinal section of the device, showing the slide valve and plunger thereof at one terminal of movement, Fig. 3 is a view similar to Fig. 2, showing the slide valve and plunger at the other terminal of their movement, Fig. 4 is a section taken on line *x*—*x* of Fig. 3, and Fig. 5 is a section taken on line *y*—*y* of Fig. 4.

35 The preferred form of construction, as illustrated in the drawings, comprises a rectangular housing or body 1 adapted, when the device is in use, to contain the oil or lubricant which it is desired to feed to the engine in conjunction with which the device is employed. Said housing 1 is provided with a cover 2 which is hinged at one side as at 3 to said housing, the opposite side of said cover being releasably locked in 45 closed position by means of screws 4 pivotally secured at their lower ends as at 5 to the housing 1, thumb nuts 6 threaded upon the free ends of said screws being adapted for coöperation with bifurcated 50 lugs 7 formed upon said cover. If desired the pivotal connection between said cover and housing may be dispensed with and in lieu thereof the screw and thumb nut connection, employed at the opposite side of the 55 cover, also used at this side.

The bottom of housing 1 is comparatively thick, as seen, and is formed at its upper side with a central longitudinally extending channel 8. The central portion of the channel 8 is covered by a plate 9 countersunk in the upper side of the bottom member of the housing and secured thereto by bolts 10. Provided in the plate 9 is a slot 11 hereinafter referred to as the inlet passage leading to the chamber constituted by the channel 8 below plate 9. Leading from the under side of said chamber is an outlet passage 12.

Mounted for reciprocation in channel 8, below the plate 9, is a plunger 13 and a slide valve 14 arranged end to end. Said plunger and slide valve are connected by means of a stem 15 projecting from said plunger which loosely engages in an opening 15' formed in the adjacent end of said slide valve. 70 Threaded upon said stem is a nut 16 which is positioned in a recess 17 formed for the reception thereof in said slide valve. Said recess is of a shape in cross section adapting the same to snugly receive the nut 16, as 75 clearly shown in Fig. 4, whereby said nut is locked against relative rotary movement and hence adjustment of the parts, after once being set, is prevented except upon detachment of the plate 9 and removal of the 80 plunger and valve from the channel 8, it being clear that, when thus removed, said plunger and valve may be relatively rotated.

The arrangement is such, as will be seen, that an operative connection between the 90 plunger and valve is provided wherein lost motion is afforded said valve and with the result that, upon reciprocation of said plunger, a pocket A will be formed between the adjacent ends of said plunger and valve. 95 This pocket, when the plunger is at its left hand terminal of movement, as seen in Fig. 2, will be in registration with the slot 11, permitting of the entrance of oil thereinto. As said plunger is moved to the right, some 100 of the oil thus admitted will be returned or squirted upwardly through said slot until the right hand end of said plunger passes the remote edge of said slot, whereupon a certain quantity of oil will be imprisoned in the pocket A between the adjacent ends of 105 said plunger and valve. The oil thus imprisoned will be carried to registration with the passage 12. Coöoperating with the slide valve 14 is a stop member 18 adapted to en- 110

gage with said valve as the plunger 13 approaches its right hand terminal of movement and arrest the movement of said valve, so that upon continued movement of said plunger, the oil contained in the pocket A will be forced therefrom into the passage 12, as shown in Fig. 3.

The passage 12 is controlled by a check valve 19 which serves to prevent backing up into the pocket A, said check valve being moved to open position by the pressure of the oil forced into the passage 12 by the plunger 13, as above mentioned. The pressure upon the oil exerted by the plunger 13 is sufficient to overcome the influence of the spring coöperating with said check valve and also the steam pressure within the engine cylinder. The upper side of check valve 19 is spaced slightly from the under side of slide valve 14 so as to insure an even distribution of pressure upon said check valve and thus prevent binding of the same when actuated. Upon movement of said check valve to open position, the oil flows around the same through passages 20 into pipe 21 which leads to the engine cylinder which it is desired to lubricate. The ports of passages 11 and 12 communicating with the channel 8 are so spaced that at no time will the pocket A simultaneously register with both, such an arrangement insuring against draining of the oil from housing 1 in the event of suction created in pipe 21, such as results as for instance when a locomotive is drifting without the engine being in operation, it being known that in the latter case, vacuums are formed in the cylinders of the locomotive. Reciprocation of the plunger 13, as described, is effected by means of an enlargement or head 22 formed at one end of said plunger in which is provided a vertically elongated slot 23 with which coöperates an eccentric 24 carried by a shaft 25 rotatably mounted in housing 1. The bearings 26 at one end of shaft 25 are inclosed in a liquid tight cap 27, the opposite end of said shaft projecting exteriorly through a suitably packed bearing 28 and being equipped with a ratchet wheel 29. Loosely mounted upon the corresponding end of said shaft is a housing 30 in which is carried a pawl 31 adapted, upon oscillation of the member 30, to engage with the teeth of ratchet wheel 29 and thus effect intermittent rotary movement of shaft 25 with the resultant reciprocation of plunger 13, as desired. The member 30 is formed with a stem 32 in which is provided a plurality of spaced perforations 31 which afford means of connection by means of a link or arm with any suitable reciprocating portion of the engine whereby the member 30 may be oscillated. A plurality of perforations 33 is provided in order to afford adjustment of the throw of the stem 32 and

hence regulation of the feed of oil to the engine.

The device set forth is of course designed for use in connection with one cylinder, it being understood that where the steam engine to be lubricated embodies more than one cylinder, a plurality of devices as described will be employed, one coöperating with each cylinder. Where more than one device is employed, the same may be driven separately or arranged abreast or united into one construction with very little change in the details described.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A device of the class described comprising a housing; an elongated chamber; an inlet passage to said chamber establishing communication between the latter and the interior of said housing; an outlet passage leading from said chamber; a plunger and a slide valve mounted for reciprocation in said chamber; and an operative connection between said plunger and said valve affording lost motion for the latter and whereby, upon reciprocation of said parts, a pocket is formed between said parts adapted for alternate registration with said inlet and outlet passages; and means for reciprocating said plunger, substantially as described.

2. A device of the class described comprising a housing; an elongated chamber; an inlet passage to said chamber establishing communication between the latter and the interior of said housing; an outlet passage leading from said chamber; a plunger and a slide valve mounted for reciprocation in said chamber; said plunger and valve being relatively movable whereby a pocket is formed between the same; a check valve interposed in said outlet passage; a stop coöperating with said slide valve to arrest the movement thereof when said pocket is in registration with said outlet passage; and means for reciprocating said plunger, the terminals of said inlet and outlet passages communicating with said chamber being so spaced that said pocket is incapable of simultaneous registration with said passages, substantially as described.

3. A device of the class described comprising a housing; an elongated chamber; an inlet passage to said chamber establish-

ing communication between the latter and the interior of said housing; an outlet passage leading from said chamber; a plunger and a slide valve mounted for reciprocation in said chamber; an operative connection between said plunger and said valve affording lost motion for the latter and whereby, upon reciprocation of said parts, a pocket is formed between said parts adapted for alternate registration with said inlet and outlet passages, said connection comprising a stem on said plunger loosely engaging an opening in said valve; a stop member on said stem adapted for engagement with said valve; a recess in said valve for the reception of said stop member; and means for reciprocating said plunger, substantially as described.

4. A device of the class described comprising a housing; an elongated chamber; an inlet passage to said chamber establishing communication between the latter and the interior of said housing; an outlet passage leading from said chamber; a plunger and a slide valve mounted for reciprocation in said chamber; an operative connection between said plunger and said valve affording lost motion for the latter and whereby, upon reciprocation of said parts, a pocket is formed between said parts adapted for alternate registration with said inlet and outlet passages, said connection comprising a stem on said plunger loosely engaging an opening in said valve; a nut threaded on said stem adapted for engagement with said

valve; a recess in said valve for the reception of said nut adapted to prevent relative rotation of the latter; and means for reciprocating said plunger, substantially as described. 35

5. A device of the class described comprising a housing; an elongated chamber formed in the bottom of said housing; an inlet passage to said chamber establishing communication between the latter and the interior of said housing; an outlet passage leading from said chamber; a plunger and a slide valve arranged in alinement in said chamber and adapted for reciprocatory movement therein; an operative connection between said plunger and said valve affording lost motion for the latter and whereby, upon reciprocation of said parts, a pocket is formed between said parts adapted for alternate registration with said inlet and outlet passages; an enlargement on said plunger 55 having an elongated slot therein disposed at substantially right angles to the direction of movement of said valve; and a rotary eccentric engaging with said slot for effecting reciprocation of said plunger, substantially 60 as described.

In testimony whereof I have signed my name to this specification in the presence of two subscribing witnesses.

JAMES V. MOHLER.
